TILE UNIT

Glenn W. Bunday, Sunland, Calif., assignor to Ceratile Corporation, Paramount, Calif., a corporation of California

Application February 3, 1958, Serial No. 49,479

Term of patent 14 years

(Cl. D18—2)

Fig. 1 is a front elevational view of a tile unit embodying my new design.

Fig. 2 is an edge view of the tile unit shown in Fig. 1.
I claim:

The ornamental design for a tile unit, as shown.
